UNITED STATES PATENT OFFICE.

EDWARD PALMER, OF BEXLEY, OHIO.

PRINTING-PLATE HOLDER.

Application filed June 13, 1925. Serial No. 36,845.

To all whom it may concern:

Be it known that I, EDWARD PALMER, a citizen of the United States, residing at Bexley, in the county of Franklin and State 5 of Ohio, have invented certain new and useful Improvements in Printing-Plate Holders, of which the following is a specification.

The present invention is directed to improvements in printing plate holders.

10 The primary object of the invention is to provide a device of this character so constructed that the printing plates can be easily and quickly attached to or removed from the cylinder or adjusted thereon for

15 precise registration.

A further object of the invention is to provide a device of this kind constructed in such manner that the printing plate clamps can be simultaneously released to permit 20 adjustment thereof in order that the printing plates may be adjusted in various positions upon the cylinder.

A still further object of the invention is to provide a device of this nature so constructed that the printing plates can be adjusted with ease and precision and held firmly in their adjusted positions in a simple and efficient manner, the adjusting operation being extremely simple and consequently 30 saving time and labor.

With these and other objects in view this invention resides in the novel features of construction, formation, combination and arrangement of parts to be hereinafter more 35 fully described, claimed and illustrated in the accompanying drawings, in which:—

Figure 1 is a fragmentary flat plan view of the cylinder.

Figure 2 is a transverse sectional view.

40 Figure 3 is a sectional view on line 3—3 of Figure 1.

Figure 4 is a sectional view on line 4—4 of Figure 1.

45 Figure 5 is a sectional view on line 5—5 of Figure 2.

Figure 6 is a sectional view on line 6—6 of Figure 5.

Figure 7 is a sectional view, showing the bolts released.

50 Figure 8 is a fragmentary detail view of the locking plate.

Figure 9 is a perspective view of one of the locking plates.

55 Figure 10 is a detail view of the draw bar locking mechanism.

Referring to the drawings, 1 designates

the cylinder which is formed from a plurality of sections 2, preferably four in number. These sections are each provided with a plurality of rows of openings 3 extending longitudinally of the cylinder.

60 Located within said sections are hubs 4, said hubs having radial ribs 5, in this instance four in number and having their terminals suitably secured to the interior of the cylinder, there being shoulders 6 formed upon opposite sides of said ribs which form in conjunction with the cylinder wall guide grooves 7, the purpose of which will appear 65 later.

70 Disposed between the respective ribs 5 of each section are independently actuated arcuate locking plates 8, the side edges of which are adapted to engage the grooves 7 for limited sliding movement, said plates being provided with sockets 9 adapted for interlocking engagement with the lugs 10 of the respective draw bars 11, the inner edges of which are slidable in the guide grooves 12 formed in the hubs 4, there being two 75 grooves and draw bars between each pair of ribs. The draw bars vary in length, the shorter ones serving to slide the outermost locking plates, while the longer ones actuate the innermost plates of the respective 80 sections. These locking plates are provided with a plurality of longitudinal rows of key-hole slots 13, corresponding in number to the openings 3. The longitudinal walls of these slots are beveled, as at 14, and taper 85 longitudinally so as to produce a wedging action when the locking plates are moved in one direction.

85 In order to shift the draw bars 11, and thus the locking plates 8 when desired each end of the cylinder has associated therewith bolts 15 which are capable of being screwed inwardly or outwardly a sufficient distance to slide the associated parts to perform their respective functions. The heads 16 of these 100 bolts are circular and are adapted to engage between the wings 17 carried by the outer ends of the draw bars 11 so that when the bolts are moved inwardly or outwardly the locking plates will be correspondingly moved, 105 as will be obvious. The heads 16 are provided with wrench engaging heads 18 to facilitate the rotation of the bolts. The heads 16 are further provided with notches 19 adapted to be engaged by the pawls 20 110 suitably pivoted upon the ends of the cylinder, said pawls serving, when engaged

with the notches to prevent accidental rotation of the bolts in order to hold the locking plates positively in their locked positions.

The printing plates 21 are of conventional form as are the clamping plates 22 therefor, with the exception that the latter are provided with transverse beveled walled slots 23 to permit precise adjustment thereof. Co-operatively associated with the plates 22 are pins 24 which have their beveled heads engaged in the slots 23 and their shanks selectively engaged in the openings 3, said shanks being provided with annular grooves 25 and resultant annular shoulders 26. The shoulders 26 are of such diameters that they can pass freely into or out of the circular portions of the key-hole slots 13, but will be bindingly engaged by the longitudinal portions of said slots when the locking plates 8 are in their operative or locked positions.

Owing to the presence of the ribs 5 comparatively short pins 27 are required, said pins being otherwise identical with the pins 24, said pins being co-operatively associated with the longitudinal dovetail slots 28 formed in the sections 2 of the cylinder. Occupying the bases of the slots 28 are draw bars 29 and 30, varying in length and arranged side by side, said bars being provided respectively with open slots 31 and key-hole slots 31' adapted to co-operate with the pins 27 as do the slots 13 with the pins 24, there being filler strips 32 engaged in the slots 28 which are provided with openings 33 for accommodating the pins 27.

The adjacent ends of the plates 8 are provided, respectively, with lugs and recesses 33' and 34, the recesses having open slots 35 therein which co-operate with the lugs and function in the same manner with the pins 27 as do the slots 13 with the pins 24.

To apply a printing plate to the cylinder, the locking plates 8 are slid in a direction to cause the circular portions of the slots 13 to register with the openings 3, after which the clamping plates 22 are successively adjusted in holding relation with the printing plate, whereupon the pins 24 are dropped in the openings. Upon rotating the desired bolt 16 the associated locking plate 8 will slide to cause the shoulders 26 to ride upwardly upon the beveled walls 14 of the slots 13, thus drawing the pins inwardly and causing the heads thereof to hold the clamping plates tightly engaged with the margins of the printing plates at the desired points.

It will be obvious that by arranging the openings 3 as shown that the printing plates 21 can be placed in any desired position upon the cylinder for effective operation and proper registration during the printing operation.

The draw bars 29 and 30 are shifted

through the medium of the heads 35' of the bolts 36, said bolts being arranged to operate in the same manner as the heads 16 operate in connection with the draw bars 11.

While I have shown my invention used in connection with a printing cylinder it will be of course understood that by minor changes in the construction it can be used with equal success with flat or platen presses.

From the foregoing, it is thought that the construction, operation and many advantages of the herein described invention will be apparent to those skilled in the art, without further description, and it will be understood that various changes in size, shape, proportion, and minor changes in details of construction may be resorted to without departing from the spirit of the invention.

What is claimed is:—

1. The combination with a printing plate support having a plurality of openings therein, of locking plates slidably associated therewith, clamping plates for the printing plate, means passable through the clamping plates and engageable with the locking plates for holding the clamping plates engaged with the printing plate, and means for shifting the locking plates, as and for the purpose set forth.

2. The combination with a plate having a plurality of openings formed therein, of locking plates slidably engaged with the plate and having slots therein, clamping plates upon the plate for engaging the printing plates, pins passable through the clamping plates and openings for engagement in said slots, and means for sliding the locking plates to hold the clamping plates in binding engagement with the printing plate.

3. In a printing plate holder, the combination with a plate having a plurality of openings therein, of locking plates slidable under the plate, draw bars interlocked with the locking plates, clamping plates engaged with the printing plate, pins passable through the clamping plates and openings for engagement with the locking plates, and means for sliding the draw bars and thus the locking plates to cause the locking plates to hold the pins in binding engagement with the clamping plates, as and for the purpose set forth.

4. In a printing plate holder, the combination with a plate having a plurality of openings therein, of a plurality of locking plates slidably associated with the plate, clamping plates for the printing plates, pins passable through the clamping plates and openings and engaged with the locking plates to hold the clamping plates in binding engagement with the printing plates, and means for sliding the locking plates independently.

5. In a holder for printing plates, the combination with a cylinder, of a plurality

of locking plates slidably associated with the cylinder, clamping plates for the printing plates, means passable through the clamping plates and cylinder for engagement with the locking plates, draw bars connected with the locking plates, adjustable devices upon the ends of the cylinder for selectively sliding the draw bars and thus the locking plates to cause the locking plates to actuate the said means to hold the clamping plates engaged with the printing plates.

6. In a holder for printing plates, the combination with a cylinder having a plurality of rows of openings therein, hubs located in the cylinder, locking plates slidably associated with the hubs, draw bars interlocked with the locking plates and slidable upon the hubs, clamping plates for the printing plates, pins engaged in the clamping plates and selected openings, said lock-

ing plates having slots therein for engagement with the pins to hold said pins in clamped engagement with the clamping plates and the clamping plates engaged with the printing plates, and means for sliding the draw bars to slide the locking plates, as and for the purpose set forth.

7. In a holder for printing plates, the combination with a plate, of a plurality of locking plates slidably associated with the plate, clamping plates for the printing plates, pins engageable with the clamping plates and locking plates, and means for operating the locking plates in reverse directions to cause the pins to bindingly hold or release the clamping plates, as and for the purpose set forth.

In testimony whereof I affix my signature.

EDWARD PALMER.
